C. R. HELLSTROM

DISPENSING CABINET

Filed June 7, 1924

Patented Sept. 7, 1926.

1,599,175

UNITED STATES PATENT OFFICE.

CARL R. HELLSTROM, OF WASHINGTON, DISTRICT OF COLUMBIA.

DISPENSING CABINET.

Application filed June 7, 1924. Serial No. 718,528.

The invention relates to dispensing cabinet for interleaved paper, such as toilet paper, paper towels, paper napkins, and the like, and has as an object the provision of a cabinet provided with a vertical slot, through which the paper may be dispensed, and toward which it may be pressed by means of a sliding weight within the cabinet.

A further object of the invention is the provision of a cabinet which may be housed within a wall and to which access may be gained by the fact that the front is hinged adjacent its lower corner.

A further object of the invention is the provision of means to prevent the weight from falling out of the cabinet when the same is opened.

A further object of the invention is the provision of means for efficiently securing the weight-controlling means to the walls of the cabinet casing.

Further objects of the invention will appear from the following description when read in connection with the accompanying drawing, in which—

Figure 1 is a perspective view of one form of the cabinet in place in a wall. Fig. 2 is a perspective view of the form of Fig. 1 removed from the wall and shown in open position. Fig. 3 is a perspective view of a modification shown in open position. Fig. 4 is a perspective view of a still further modification. Fig. 5 is a perspective view of a form of the invention provided with a horizontal slot and shown in place in the wall. Fig. 6 is a detail section on line 6, 6 of Fig. 2.

As shown in Fig. 1, the device comprises a casing 10, adapted to be recessed into a wall, and provided with a flange 11 around its front edges to overlap the edges of the wall opening to neatly cover the joint between the casing and the wall.

Within the casing 10, there is shown a box 12, comprising a front plate 13, sides 14, 15, and a bottom 16, constituting a box, open at the top and rear sides. As shown, the box is pivoted at its lower front corner, at 16, to the wall of the casing 10, so as to swing outwardly, and may be provided with a lock diagrammatically shown at 17, and of any desired nature, for its retention in closed position.

In the form of the device shown in Figs. 1 to 4 inclusive, the front 13 of the cabinet

is provided with a vertical slot 18, preferably having its edges out-turned, as at 19.

To feed a package, 20, of interleaved sheets of paper toward the slot 19, there is shown a weight 21, acting by gravity, upon ways 22 mounted upon the sides 14, 15 of the box 12, in the form of the device shown in Figs. 1, 2, 4 and 5.

As shown in the drawing, this weight is made in the form of a cylinder preferably solid, and can conveniently be formed by cutting lengths from a stock rod of steel substantially one-half inch in diameter. The size of the rod will have effect upon the placing, and angle of the ways upon which it slides. Since a one-half inch rod may be effective in use and does not occupy an inordinate amount of space within the cabinet, it is the size preferred. With a rod of this diameter formed of steel or cast iron, it is found that the ways 22 should be placed at an angle of substantially 48° to the horizontal, and in position such that the center of the way is somewhat below the center of the height of the cabinet. The reason for the placing of the ways below the center, as described, is the fact that the resistance to movement of the sheets of paper is largely due to their friction against the bottom end 16 of the box within which the sheets are housed. With weights of other sizes, material, or shape from that disclosed, the placing and angle of the ways should be such as to produce substantially the same propelling force as will be provided by the weight of one-half inch diameter formed of steel and acting upon ways placed at 48° to the horizontal. The angle and location of the ways is that described and claimed in my Patent No. 1,497,562, issued June 10, 1924.

In the form of the device of Fig. 3, the ways 22' are carried upon the inner walls of the casing 10 and the slot is formed in the front 13, hinged at its lower corner 23, and provided with a sector 24 having a slot 25 into which a pin 26 projects to limit the outward movement of the front. The outward movement of the front in this form of the device is limited to an angle of less than 90° to the vertical, in order that when closed the weight 21 may be forced up to the ways 22 to the active position, when the front with the pack of paper in place is closed.

To prevent the weight 21 from falling

- out of the cabinet and to hold the same out of the way when the paper in the cabinet is being replenished, a piece of fabric 27 is shown secured within the casing 10, and 5 preferably at the upper rear corner thereof, and is secured to the weight 21 in any desirable manner, as for instance by inserting the weight into a hem in the fabric. To provide for control of the fabric 27 when the 10 device is open, as shown in Fig. 2, a rod 28 may be passed through openings in the upper rear corners of the sides 14, 15 of the box, over which the fabric may draw when the box is opened, thereby pulling the 15 weight to the position shown in Fig. 2 out of the way of the placing of the new supply of paper in the cabinet, but not interfering with the motion of the weight upon the ways by gravity when the box is closed.
- 20 A convenient method of attaching the fabric 27 within the casing provided by the invention is that shown in detail in Fig. 6, showing the fabric 27 folded with the lock seam 29, by means of which the corners of the casing 10 are preferably joined.

25 The form of the device of Fig. 4 is designed to dispense paper towels folded in interleaved style, and differs from the form of Figs. 1 and 2 only by its relative proportions.

30 In Fig. 5 is shown a form of the invention, the pivoted box 13 provided with sides 14, 15, but with the slot 18' in the front of the box in a horizontal position instead of a vertical position.

35 The advantage of a vertical slot is that the feeding of paper to such a slot is found to be less critical than is the case with a horizontal slot. This is true since in order 40 to feed interleaved paper so that the end of each successive sheet will be pulled out of the slot so as to be accessible, the packet of paper must be pressed with substantial uniformity against the two sides of the slot, 45 since if the paper lies away from one side thereof the end of one of the sheets will not be drawn through the slot. With a vertical slot, even though a portion of the pack lies away so that the pack occupies a 50 position at an angle to the vertical within the front of the casing, yet some point will exist either at the upper or lower end of the slot where the pack contacts with the front of the slot in a horizontal zone, in 55 which zone the pack will bear against the two sides of the slot with substantial uniformity. Therefore some portion of the side of the leading edge of the sheet will be

drawn through the slot and the remainder of the edge will follow. While it is not considered that the vertical slot is so convenient in use, since a vertical motion of the hand of the user in removing the paper may tear the sheet instead of pulling the same from the slot, yet in some locations this 60 form of the device is permissible, and when it can be used will be found to work with more certainty than the form shown in my patent above referred to.

65 Minor changes may be made in the physical embodiment of the invention without departing from its spirit.

70 I claim:

75 1. A paper dispensing cabinet comprising a casing adapted to be housed in a recess in a vertical surface, a front wall for said casing hinged at the lower front corner of the casing, a vertical slot located substantially centrally of said front, means to limit the outward movement of said front, downwardly and forwardly sloping ways, the 80 central point of said ways being adjacent the center of the height of the casing, a gravity actuated weight traveling upon said ways to press paper against the front of said 85 casing, and means within the casing to draw said weight to the upper end of the ways when the casing is open.

90 2. A paper dispensing cabinet comprising, in combination, a casing adapted to be housed in a recess in a vertical surface, a box having a vertical slot substantially centrally located in its front wall, said box hingedly connected to said casing at its lower front corner and adapted to close therewithin, downwardly and forwardly inclined ways within said box when the box is closed, a gravity actuated weight traveling upon said ways and adapted to press paper housed within said box with substantial uniformity against the two sides of the slot.

95 3. A paper dispensing cabinet comprising, in combination, a casing adapted to be housed in a recess in a vertical surface, a box having a vertical slot adjacent the central portion of its front wall, said box hingedly connected to said casing at the lower front corner of each, ways carried by the surfaces of the side walls of said box downwardly and forwardly inclined when the box is 100 closed, a gravity actuated weight traveling on said ways and adapted to press paper within said box against the two sides of said slot with substantial uniformity.

CARL R. HELLSTROM.
